UNITED STATES PATENT OFFICE.

AUSTIN F. JACKSON, OF TAUNTON, MASSACHUSETTS.

DESIGN FOR A SPOON, &c.

SPECIFICATION forming part of Design No. 20,974, dated August 4, 1891.

Application filed July 7, 1891. Serial No. 398,728. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons, Knives, Forks, Ladles, &c., of which the following is a specification, reference being had to the accompanying drawings, forming part thereof.

Figure 1 is a view of the upper face of a spoon, showing my design. Fig. 2 is a view of the under or lower face of the spoon, showing my design.

The leading feature of my design for the upper face consists of a leafy scroll $s s s^2 s s$, whose general shape resembles the letter **S**, the said scroll having about its middle a flower s^2 . Another flower s^3 appears on the handle next to the shank, which latter is wrought at a into longitudinal corrugations and at b has a wrapping of leaves. Upon the

under face the chief features are a palette-shaped panel c and adjoining this on the outer end a strongly-marked leafy scroll terminating in a volute coil t . Below the panel or next to the shank appears a flower d , while the shank itself is ornamented with longitudinal corrugations and overlaid leaves l . The outlines of the handle are irregular and rough, being formed by the irregular edges of the scroll-work.

What I claim is—

1. The design for the upper face of the handles of spoons, knives, forks, ladles, &c., substantially as shown and described. 35

2. The design for the lower face of the handles of spoons, knives, forks, ladles, &c., substantially as shown and described.

AUSTIN F. JACKSON.
